UNITED STATES PATENT OFFICE

158,437

SHOE OR SIMILAR ARTICLE

Aaron Briefda, Los Angeles, Calif.

Application November 17, 1949, Serial No. 6,096

Term of patent 14 years

(Cl. D7—7)

To all whom it may concern:

Be it known that I, Aaron Briefda, a citizen of the United States and residing at Los Angeles, in the county of Los Angeles, State of California, have invented a new, original, and ornamental Design for a Shoe or Similar Article, of which the following is a specification, reference being had to the accompanying drawing, forming part thereof, in which:

Fig. 1 is a perspective view of a shoe or similar article, showing my new design:

Fig. 2 is a view in side elevation:

Fig. 3 is a front view:

Fig. 4 is a back view:

Fig. 5 is a plan view.

The broken lines in the drawing indicate stitching.

I claim:

The ornamental design for a shoe or similar article substantially as shown and described.

AARON BRIEFDA.
